UNITED STATES PATENT OFFICE

LEONARDO M. TARTAGLIA, OF ALBUQUERQUE, NEW MEXICO

MUSIC LEAF TURNER

Application filed August 8, 1928. Serial No. 298,328.

This invention relates to certain new improvements in music leaf turners and more particularly to the class of such devices in which the turning arms are operated by a spring or elastic means.

The subject matter of this invention constitutes an improvement over that described and claimed in the prior United States Patent No. 1,667,908, issued to Carmine Tartaglia May 1, 1928.

One of the objects of this invention is to furnish a device which may be attached to the piano, organ or other instruments, or to a music stand and which may be operated conveniently by the performer by a slight pressure of his foot upon a switch pedal.

Another object of this invention is to provide electrically operated means in connection with a music leaf turner for controlling the operation thereof.

Another object of this invention is to provide means for controlling the operation of a plurality of music leaf turners in unison.

Still another object of this invention is to provide a device whose construction is simple and durable and not likely to get out of order or become disarranged.

With these and other objects in view which may be incident to my improvements, the invention consists in the parts and combinations to be hereinafter set forth and claimed, with the understanding that the several necessary elements comprising my invention, may be varied in construction, proportions and arrangement, without departing from the spirit and scope of the appended claims.

My improved device consists of a base which may be mounted above the keyboard of a piano or upon a base such as is commonly used for music stands, and upon which is preferably mounted a metallic rest bent slightly outwardly from a vertical central line. The lower edge of the rest is turned upwardly at an angle to the body portion thereof, so as to afford a suitable support for a music book.

A suitable binding rod or narrow plate is positioned vertically down the center line of the book, so as to hold it in proper position.

From an upper support extend lateral arms

adapted to be connected with the sheets or pages of said book to turn the same. These arms are mounted in a horizontal plane substantially parallel to the upper edges of the sheets of music, and their operation is controlled by a suitable electro-magnetic mechanism, adapted to be operated by the foot of the musician. To turn the sheets of music from an initial position at the right of the music rest to the left side thereof, it is necessary only for the musician to touch a switch button with his foot.

In order to make my invention more clearly understood, I have shown in the accompanying drawings means for carrying the same into practical effect, without limiting the improvements in their useful applications to the particular constructions, which for the purpose of explanation, have been made the subject of illustration.

In the drawings:

Figure 1 is a front view showing a music book mounted upon the music rest, and the manner of securing leaves to the turning or carrying arms, together with the electro-magnetically operated release mechanism.

Figure 2 is an enlarged detailed side elevation of the electro-magnetically controlled mechanism for retaining and releasing the leaf carrying arms.

Figure 3 is a detailed view of the electro-magnetically operated release mechanism taken on line 3—3 of Figure 2.

Figure 4 is a sectional view through the electromagnet, taken on line 4—4 of Figure 2.

As shown in Figure 1 my invention comprises a baseboard 1 which may be mounted above the key-board of a piano or like instrument or on a base similar to those commonly used for music stands. Mounted on the base-board 1 is a member 2 which serves as a combined support and bearing for a rod 3.

The purpose of the rod 3 is to support a series of carrying or turning arms 4 which pivot thereon. Each of these arms is preferably formed from metal and is bifurcated to form an upper member or shank 5 and a lower member 6, the upper member being longer than the lower, and provided near its

outer end with a snap hook 7. The lower member is resilient and is adapted to be sprung into hook 7.

It will also be noted that each upper member 5 is provided with an ear 8. The inner end of a member 4 is bent upwardly for a short distance, then at right angles to form a portion that is parallel to the main body and which is apertured, so as to fit over and 10 turn on the rod 3. The upper left portion of the base-board 1 is provided with a hook 9, to which is attached one end of a series of elastic bands 10, the free ends of which extend across the guide 11, and are each fastened to one of the series of turning arms 4 by means of the ears 8.

As soon as one of the arms 4 becomes free to move as will hereinafter appear, the elasticity of the band 10 imparts momentum to 20 said turning arm and causes the latter to move from a position on one side of the rod 3, to a position on the other side thereof. The points of attachment of the elastic bands are such that the drag upon the leaf carrying 25 arms will be exerted in practically the same plane, thus insuring smooth operation of the arms. Of course the guide 11 projects from the base-board 1 a distance sufficient to cause the bands 10 to move the arms 4 from one 30 side to the other.

Mounted a suitable distance below the member 2 on the base-board 1 is a shelf or rack 12 adapted to support a book of music. The shelf or rest is so shaped as to prevent 35 the sheets supported thereby from slipping or being accidentally displaced. The central portion of the shelf 12 is cut away to permit the lower portion of a binding rod 13 carried by the lower end of rod 3 to engage with 40 a hook 14.

Figure 1 shows a music book arranged in place on the rack 12 and held in position by the binding rod 13. Each of the pages or leaves of the book is provided adjacent its 45 upper edge with a plurality of grommets 15. The free ends of the grommets are provided with eyelets through which the lower portions 6 of the turning arms pass.

Upon the upper part of the base-board is 50 secured an electro-magnetically controlled device 16, adapted to cooperate with the free ends of the arms 4 to retain them in position and release them one at a time.

As shown in Figure 2 the arm release 55 mechanism comprises a horizontally extending block 17 of suitable material secured to base-board 1 and provided on the end thereof with a nose 18. Also secured to the base-board 1 immediately beneath the block 17 and 60 helping to sustain the same is another block 19. The latter is provided with openings adapted to receive rods 20 and 21 secured to plate 22 which is held in position by the block 19. These rods carry springs 23 and 24, 65 which yieldingly act on a follow plate 25 slid-

ably mounted on the rods 20 and 21. Suitable plates 26 are mounted on the lower block 19 and extend out from base-board 1 parallel to the block 17 to provide a support for the ends of arms 4.

Plates 26 extend laterally from the base-board 1 to a point adjacent the nose member 18. There is sufficient space laterally between the nose 18 and plates 26 to permit an arm 4 to pass therebetween, but the vertical 75 space between the plates 26 and nose 18 is small enough so that the nose 18 will retain the arms in position. Spring means 38 are mounted on the plates 26 to prevent the arms 4 accidentally slipping between the nose 18 80 and plates 26 to be released.

Mounted on the top of block 17 is an electrically operated device adapted to release the arms 4 held between block 17 and plates 26 by the nose 18. This device comprises a coil of wire 27 wound on a spool 28. A cup shaped device 29 is secured on the top of block 17 by securing means 30, and serves as a receptacle for the spool 28, carrying the 85 coil of wire 27.

Spool 28 is cored, forming a space 31 in which a suitable armature 32 susceptible to magnetism operates. An abutment 31' is fixed in the bottom of the space 31 to limit the downward movement of the armature 32. 90 The abutment 31' and the armature 32 are of such sizes that the bottom of a yoke 33, carried by the armature 32, and adapted to move in a vertical path, will extend below the nose 18 on the down stroke of the armature 32.

The armature 32 is attached to a yoke 33 adapted to move in a vertical path. Guide members 34 are carried by the casing 29 of the solenoid and serve to restrict the movement of the yoke 33 to a vertical path. Attached to the upper portion of the yoke 33 is a spring member 35 which is supported by a bracket 36, securely mounted on the top of block 17 by fastening means 37. The spring operates to retain the yoke 33 and the attached armature 32 in an elevated position.

The material forming yoke 33 is of a size smaller than the thickness of arms 4. Yoke 33 is adapted to bear on an arm 4 to force the same past the nose 18 against the action of spring 38 to permit the release thereof. When the first arm 4 is released the springs 23 and 24 cause the follow plate 25 to push the group of arms 4 forward until one of the 110 arms contacts with the nose 18.

The coil 27 of the solenoid is connected in series by wiring 39 with a suitable foot operated switch 40 to a source of electricity. When the switch 40 is operated, an electric current flows through the same and the coil 27 of the magnetic device. This causes a magnetic flux to be set up which causes the armature 32 to be drawn downwardly into the solenoid. The downward movement of 120 125 130

the armature 32 of course causes the yoke 33 to move downward forcing one of the arms 4 past nose 18 to be released. When the current is shut off, spring 35 pulls the armature 32 and yoke 33 back to their former position.

In operation a music book having leaves provided with suitable grommets is placed on the rack 12 of the baseboard 1; the lower parts 6 of arms 4 are passed through the grommets and engaged with the hooks 7. The binding rod 13 is secured in place to retain the book in position and hold the pages, for proper turning. After all necessary adjustments are made the arms 4 are turned to the right and secured between block 17 and plates 26 by the nose 18 and cooperating spring 38 as shown in Figure 2. In performing, when the musician desires a page to be turned, he operates the foot switch 40, requiring very little exertion on his part, to permit the electric current to flow through the coil 27.

The electric current in flowing through coil 27 causes a magnetic flux to be set up, which affects the armature 32 causing it to be drawn into the core of the solenoid. Due to this action the attached yoke 33 moves downwardly and pushes an arm 4 past the nose 18 against the force of spring 38. When the musician's foot leaves the switch 40, the armature and yoke are drawn upwardly into their former position by the spring 35. The springs 23 and 24 act on the follow plate 25 pushing the group of arms 4 forward until the first one engages the nose 18.

When one of the arms 4 is released from the mechanism 16, the tension in the elastic band 10 causes the arm to move over to the other side, thereby turning the page of the music book.

If desired, a plurality of music leaf turners may be electrically connected so as to be operated in unison by a single control switch. For instance, in the case of an orchestra, the switch could be operated by the orchestra leader, relieving the musicians from the necessity of turning pages. Such an arrangement would also be desirable in turning to particular selections.

Thus it can be seen that this invention affords a means of turning pages of music in a manner requiring a minimum effort on the part of the musician. My invention also serves to retain the leaves of music in position, which is particularly desirable in the case of loose sheets of music.

While I have shown and described the preferred embodiment of my invention, I wish it to be understood that I do not confine myself to the precise details of construction herein set forth, by way of illustration, as it is apparent that many changes and variations may be made therein, by those skilled in the art, without departing from the spirit of the in-

vention, or exceeding the scope of the appended claims.

I claim:

1. In a music leaf turner for use with music leaves having eyelets thereon, a base-board, a rod mounted on the base-board, a bifurcated arm mounted upon the rod, a downwardly projecting hook on one fork of the arm, the other fork adapted to be engaged by the hook and adapted to engage the eyelets on the music leaves, a downwardly projecting finger at the free end of the arm and electrically controlled means operatively associated with said finger.

2. In a music leaf turner a plurality of pivoted bifurcated arms, a hook for securing the bifurcations of each arm together, one of the bifurcations of each arm engaging eyelets on a leaf of music, a curved guide above said arms, elastic members secured to each of the arms and a stationary hook and passing over the curved guide, a release mechanism engaging the free end of each bifurcated arm and adapted to release the arms consecutively, and electric means for operating said release mechanism.

3. In a music leaf turner for use with music leaves having eyelets thereon, a base-board, a rod mounted on the base-board, a plurality of turning arms pivotally mounted upon the rod, each arm comprising a shank, a bifurcated arm integral with the shank, a hook carried by one of the bifurcations adapted to engage the free end of the other bifurcations, one of the arms being longer than the other and provided with a downwardly projecting finger on the free end thereof, and electrically operated means for controlling the operation of said arms.

4. In a music leaf turner for use with music leaves having eyelets thereon, a bracket, a plurality of turning arms pivotally mounted upon said bracket, each turning arm comprising a shank having an integral arm, a spring attaching ear upon the arm, a downwardly directed hook carried by the arm, a downward projection upon the free end of the arm engaging a releasing mechanism, a stem integral with the arm adapted to be received and held in close position by said hook and to engage the eyelets on the music leaves and electrical means for operating said release mechanism.

5. In a music leaf turner for use with music leaves having eyelets thereon, a base-board supporting a rod, a spring-actuated arm pivotally mounted upon said rod and having a hook and stem thereon, said stem adapted to engage eyelets on the music leaves and be held in a closed position by said hook, and electrically operated means for controlling movement of said arms.

6. In a music leaf turner, a plurality of spring actuated turning arms, spring actuated means for retaining a plurality of said

arms in one position and releasing them one at a time, including an electro-magnetically operated yoke.

7. In a music leaf turner having a plurality of turning arms, elastic means for actuating said arms, means for retaining a plurality of said arms in one position, comprising a block having an overhanging projection, spring means for retaining said arms behind said projection and electric means for moving said arms past said projection.

8. In a music leaf turner having a plurality of turning arms, elastic means for actuating said arms, means for retaining a plurality of said arms in one position, comprising a block having an overhanging projection, spring means for retaining said arms behind said projection and means operated by a solenoid for moving said arms past said projection.

9. In a music leaf turner having a plurality of turning arms, elastic means for actuating said arms, means for retaining a plurality of said arms in one position, comprising a block having an overhanging projection, spring means for retaining said arms behind said projection and a yoke operated by a solenoid for moving said arms past said projection, one at a time.

10. In a music leaf turner a plurality of turning arms carrying leaves of music, elastic means for actuating said arms, means for retaining said arms in one position and releasing them one at a time comprising a projection, means for retaining said arms behind said projection, a solenoid operated yoke adapted to move said arms past said projection, and means for returning said yoke to its normal position.

49. In testimony whereof I affix my signature.
LEONARDO M. TARTAGLIA.
